WHEEL DRIVEN STONE GATHERING
MACHINE

Charles A. Egstad, Badger, Minn.

Application November 21, 1950, Serial No. 196,862

3 Claims. (Cl. 55—17)

1

This invention relates to a wheel-driven, stone-gathering machine.

An object of this invention is to provide a stone-gathering machine which is particularly adapted to traverse a field having random dispersed stones thereon for arranging said stones in neat, orderly rows.

Another object of this invention is to provide a stone-gathering machine adapted to traverse a relatively wide span of the field that has been cultivated in a manner to expose stones and to collect these stones in said span and arrange said exposed stones in a row disposed centrally of said span.

A further object of this invention is to provide a stone-gathering machine which is provided with novel supporting means on the stone-collecting arms to thereby adapt the machine to run over obstructions in a manner to avoid injury to said machine.

A still further object of this invention is to provide a stone-gathering machine which is particularly adapted for attachment to a piece of farm equipment, such as a tractor.

A still further object of this invention is to provide a wheel-driven stone-gathering machine which is relatively simple in structure and cheap to manufacture.

The above and still further objects and advantages of the invention will become apparent upon consideration of the following detailed description of the invention when taken in conjunction with the accompanying drawings, wherein:

Figure 1 is a top plan view of the stone-gathering machine of the present invention shown traversing or straddling a relatively wide span of a field that has been cultivated, in a manner to expose stones;

Figure 2 is an enlarged detail view, with parts broken away and shown in section, of the stone-collecting arm of the machine of the present invention;

Figure 4 is a sectional view taken along the line 3—3 of Figure 2;

Figure 4 is an enlarged sectional view taken substantially along the line 4—4 of Figure 1;

Figure 5 is a fragmentary sectional view taken substantially along the line 5—5 of Figure 2;

Figure 6 is a rear elevational view, with parts in section, showing the rear supporting legs and wheels of the mobile frame of the stone-gathering machine of the present invention; and

Figure 7 is an elevational view, with parts broken away and shown in section, of a modi-

fied form of the stone-collecting arms for use in conjunction with the stone-gathering machine of the present invention.

Referring now more particularly to the drawings, wherein like reference numerals have been used throughout the several views to designate like parts, there is shown the wheel-driven, stone-gathering machine of the present invention, generally designated by the reference numeral 10, which is adapted to traverse a predetermined span of a field 11 having randomly dispersed stones 12 scattered thereabout, the stones being exposed, due to the cultivation of the field.

15 The machine 10 is adapted for attachment to any suitable piece of farm equipment, such as a tractor, and comprises a mobile frame 13 including rotatable ground-engaging wheels 14, 15, and a pair of rearwardly converging supporting bars 16, 17, having their convergent ends spaced from each other. The converging supporting bars 16, 17 are supported in spaced-apart relation with respect to each other by means of the crossbars 18, 19 and 20, which extend between the bars 16, 17 and are secured therebetween by welding or any other suitable means. Extending longitudinally of the mobile frame 13 are the spaced brace bars 21 and 22, which are secured to the crossbars 18, 19 and 20, and the 20 converging supporting bars 16, 17, and have end portions projecting rearwardly of the spaced convergent ends of the supporting bars 16, 17. As clearly shown in Figure 1, the spaced bars 21, 22 cooperate with the crossbars 18, 19 and 20 to maintain the convergent ends of the supporting bars 16, 17 in spaced-apart relation with respect to each other. Mounted on the rearwardly projecting ends of the bars 21, 22 are the depending legs 23, 24 which have their upper ends 25, 25 26 rotatably journaled on the bars 21, 22 for rotary movement about vertical axes and have their lower ends 27, 28 disposed substantially horizontally and carrying the rear ground-engaging wheels 29, 30. The rear ground-engaging wheels 29, 30 and the front ground-engaging wheels 14, 15 cooperate to support the main body of the frame for movement across the field to be traversed.

40 The front ground-engaging wheels 14, 15 are supported by means of the legs 31, 32, which are provided with the bearings 33, 34 for the reception of the stub shafts 35, 36 carried by the wheels 14, 15. It is to be noted that the stub shafts 35, 36 project inwardly of the bearings 33, 34 for a purpose to be subsequently described.

Positioned forwardly of the mobile frame 13 is a drawbar 37 which includes a pair of convergent arms 38, 39 having their convergent ends connected together and provided with means 40 for the attachment to the piece of farm equipment to be employed for urging the windrower over the field 11. The divergent ends of the arms 38, 39 are pivotally connected to the crossbar 18 of the mobile frame 13 by means of the hinges 41, 42. The drawbar is further provided with longitudinally extending brace bars 43, 44, each of which has one end connected to the adjacent one of the convergent arms 38, 39 and has the other end pivotally connected to the crossbar 18 by means of the hinges 45, 46.

Arranged in side-by-side spaced relation along each of the supporting bars 16, 17 are the stone-engaging and collecting arms 50. As clearly shown in Figures 2 and 3, each of the arms 50 has its upper end pivotally supported on the horizontally disposed axle 51 which is carried contiguous to and spaced below the adjacent one of the supporting bars 16, 17. Each of the stone-engaging and collecting arms 50 has its lower end turned inwardly, as designated by the reference numeral 52, Figure 3, and the inwardly turned end of the arms and the side walls thereof cooperate to form a forwardly opening scoop adapted to engage the stones 12 on the field 11. It is to be noted that the spacing of the adjacent arms 50 is selected to assure engagement with all stones of any significant size.

Suitable means are provided which are operatively connected to the ground-engaging wheels 14, 15 and engageable with the arms 50 carried by the convergent supporting bars 16, 17 for sequentially effecting the oscillatory movement of the arms 50 about the horizontal axis provided by the axle 51 in response to the rotary movement of the front ground-engaging wheels 14, 15. The aforementioned means embodies the shafts 55, 56 which are disposed longitudinally and rearwardly of each of the supporting bars 16, 17, and rotatably journaled on the mobile frame 13 by means of the spaced bearings 57, 58 carried contiguous to the supporting bar 16 and the spaced bearings 59, 60 carried contiguous to the supporting bar 17. Means, generally designated by the reference numerals 61, 62 are provided for operatively connecting the shaft 56 to the ground-engaging wheel 15, whereby, upon rotary movement of the ground-engaging wheels, a rotary movement will be imparted to the shafts 55, 56. Since each of the coupling means 61, 62 is of like structure, it will suffice to describe only one in detail. The coupling means 61 embodies a sprocket wheel 63 carried on the adjacent projecting end of the stub shaft 35 of the ground-engaging wheel 14. Disposed in substantial alignment with the sprocket wheel 63 is a second sprocket wheel 64 which is rotatably journaled on the mobile frame 13, and is coupled to the sprocket wheel 63 by means of a chain 65. As clearly shown in Figure 4, the sprocket wheel 64 is cast integrally with a hub 66 and a drive gear 67, the assembly of the sprocket gear 64, the collar 66 and the drive gear 67 being rotatably journaled on the frame 13 by means of a horizontally disposed stub shaft 68 having one end projecting through the aforementioned assembly and having the other end rotatably journaled within a bearing 69 carried by the mobile frame. The stub shaft 68 is held in place by means of a collar 70 circumposed about the stub shaft 68, and a set screw 71 extending through the collar and engaging the stub shaft.

Accordingly, upon effecting the rotary movement of the ground-engaging wheel 14, a rotary movement will be imparted to the drive gear 67 through the chain-coupled sprockets 63, 64. Carried by the adjacent projecting end of the shaft 55 is a pinion 72 which is in meshing engagement with the drive gear 67 and couples the drive gear to the shaft 55. Accordingly, a rotary movement will be effected to the shaft 55 in response to the rotary movement of the ground-engaging wheel 14. Similarly, the ground-engaging wheel 15 is coupled to the shaft 56 for effecting the rotary movement of the latter in response to the movement of the former.

To couple the arms 50 to the shafts 55, 56, each of the arms 50 is provided with a rearwardly projecting plate 73 provided with a longitudinally extending slot 74 for the extension therethrough of the adjacent one of the shafts. Since the structure for coupling the arms carried by the convergent supporting bars 16 to the shaft 55 is the same as the structure for coupling the arms carried by the supporting bar 17 to the shaft 56, it will suffice to describe only one in detail. Referring now with particularity to Figures 2, 3 and 5, there is shown the plates 73 carried by the arms 50 of the supporting bar 16 having the shaft 55 extending through the slot 74 provided in the plate 73. Fixedly secured to the shaft 55 at spaced intervals therealong are the cams 75 which are engageable with the bounding walls of the adjacent one of the slots 74 of the plates 73. As clearly shown in Figure 5, the cams 75 of the adjacent arms 50 are offset with respect to each other at a predetermined angle, to thereby sequentially effect the oscillatory movement of the arms 50 in response to the rotary movement of the ground-engaging wheels 14, 15. It is to be noted that the sequence of the oscillatory movement of the adjacent arms can be varied by selectively varying the disposition of the adjacent drive cams. Under particular operating conditions, it may be desirable to employ an angular offset other than the 90-degree offset between adjacent cams illustrated in the drawings.

In actual use, the drawbar coupling means 40 is connected to the desired piece of farm equipment, for example, a tractor, and the mobile frame 13 is then moved across the field 11 to be worked. As the mobile frame is moved across the field, the ground-engaging wheels 14, 15 will drive the shafts 55, 56 carrying the side-by-side, spaced, stone-engaging and collecting arms. The arms 50 will be oscillated in a sequence predetermined by the angular offset of the adjacent cams 75, the offset being arranged for the particular operating conditions encountered. The oscillatory movement of the arms 50 will urge the rocks 12 rearwardly along the converging supporting bars 16, 17 of the mobile frame until the rocks are deposited substantially intermediate the spaced convergent ends of the arms 16, 17, as illustrated in Figures 1 and 6. Accordingly, the normally random dispersed stones found on the cultivated field are arranged in a neat, orderly row. It is to be noted that the machine traverses a relatively wide span of the field and collects the stones in this span and forms a row disposed substantially centrally of the span. Any predetermined span width can be selected by varying the size of the mobile frame.

In Figure 7 there is shown a modified form of the stone-engaging and collecting arms to be

employed with the machine of the present invention, the modified arm being generally designated by the reference numeral 80. The modified arm 80 is particularly adapted to adapt the machine to run over obstructions in a manner to avoid injury to the structural components of the machine. The arm 80 embodies a fixed upper section 81 which has one end pivotally mounted by means of the axle 51 on the mobile frame. Disposed in end-to-end, aligned relation with respect to the other end of the fixed upper section 81 is a movable lower section 82 which is pivotally supported on the upper section 81 by means of the hinge 83'. It is to be noted that the sections 81 and 82 of the modified arm 80 are formed substantially in the same manner as is the arm 50. Operatively connecting the sections 81 and 82 together and normally maintaining said sections in alignment is a resilient means 83. The resilient means 83 illustrated is in the form of a coil spring having one end fixedly secured to the upper section 81 by means of the projecting lug 84 and has the other end connected to the section 82 by means of the projecting lug 85. It is to be noted that the resilient means 83 is disposed on the forward side of the arm 80, while the hinge pin 83' is disposed on the rearward side of the arm 80. Accordingly, upon passing over an obstruction, the lower section 82 can be urged out of the position of alignment into the broken line position illustrated in Figure 7. In this manner, when an extremely large obstruction is encountered, of a size sufficiently large to overcome the bias of the spring 83, the arms will by-pass the obstruction and thereby avoid injury to the body of the machine. It is to be noted that the plate 73 is cut away, as designated by the reference numeral 87 and is only secured to the upper section 81 of the arm 80. The plate 73 is provided with a slot 74 which is engaged by the adjacent one of the cams in the manner previously described.

It is readily apparent that numerous other modifications can be made without departing from the spirit of the invention as set forth in the appended claims.

What I claim is:

1. A stone gathering machine for attachment to a farm tractor comprising a horizontally disposed frame including a pair of supporting bars arranged in converging relation with the convergent ends being spaced from each other and spaced cross bars connecting said supporting bars together, a ground engaging wheel arranged adjacent to and supporting each of the divergent ends of said supporting bars, an axle arranged below and in longitudinal spaced relation with respect to each of said supporting bars and dependingly supported thereon, a plurality of vertically disposed arms arranged in side by side spaced relation along each of said axles and each having the upper end pivotally connected to said axle and having the lower end adapted to engage stones projecting from a ground surface, a vertically disposed plate provided with a vertical closed slot projecting longitudinally from the back of each of said arms intermediate the upper and lower ends thereof, a rotatable shaft arranged below and in parallel spaced relation to each of said axles and extending through the slots of the plates of the arms pivotally connected to the adjacent axle, a plurality of cams arranged in spaced offset relation along and fixedly carried by each of said rotatable shafts with a cam positioned within and engageable with the

bounding wall of a slot of the adjacent plate, and means drivingly connecting each of said rotatable shafts to the ground engaging wheel supporting the divergent ends of the supporting bars.

- 5 2. A stone gathering machine for attachment to a farm tractor comprising a horizontally disposed frame including a pair of supporting bars arranged in converging relation with the convergent ends being spaced from each other and spaced cross bars connecting said supporting bars together, a ground engaging wheel arranged adjacent to and supporting each of the divergent ends of said supporting bars, a pair of spaced brace bars extending longitudinally of and between said convergent supporting bars and secured to said cross bars, said brace bars having end portions projecting through and beyond the convergent spaced ends of said convergent supporting bars, a ground engaging wheel supporting each of the projecting end portions of said brace bars, an axle arranged below and in longitudinal spaced relation with respect to each of said supporting bars and dependingly supported thereon, a plurality of vertically disposed arms arranged in side by side spaced relation along each of said axles and each having the upper end pivotally connected to said axle and having the lower end adapted to engage stones projecting from a ground surface, a vertically disposed plate provided with a vertical closed slot projecting longitudinally from the back of each of said arms intermediate the upper and lower ends thereof, a rotatable shaft arranged below and in parallel spaced relation to each of said axles and extending through the slots of the plates of the arms pivotally connected to the adjacent axle, a plurality of cams arranged in spaced offset relation along and fixedly carried by each of said rotatable shafts with a cam positioned within and engageable with the bounding wall of a slot of the adjacent plate, and means drivingly connecting each of said rotatable shafts to the ground engaging wheels supporting the divergent ends of the supporting bars.
- 10 3. A stone gathering machine for attachment to a farm tractor comprising a horizontally disposed frame including a pair of supporting bars arranged in converging relation with the convergent ends being spaced from each other and spaced cross bars connecting said supporting bars together, a ground engaging wheel arranged adjacent to and supporting each of the divergent ends of said supporting bars, a pair of spaced brace bars extending longitudinally of and between said convergent supporting bars and secured to said cross bars, said brace bars having end portions projecting through and beyond the convergent spaced ends of said convergent supporting bars, a ground engaging wheel supporting each of the projecting end portions of said brace bars, a horizontally disposed drawbar positioned longitudinally of said supporting bars adjacent the divergent ends of the latter and hingedly connected to the adjacent cross bar for movement
- 15 40 from its horizontal position to an upstanding position, an axle arranged below and in longitudinal spaced relation with respect to each of the said supporting bars and dependingly supported thereon, a plurality of vertically disposed arms arranged in side by side spaced relation along each of said axles and each having the upper end pivotally connected to said axle and having the lower end adapted to engage stones projecting from a ground surface, a vertically disposed plate provided with a vertical closed
